UNITED STATES PATENT OFFICE.

MANLY M. GILLAM, OF FLUSHING, NEW YORK; ARTHUR L. GILLAM ADMINISTRATOR
OF SAID MANLY M. GILLAM, DECEASED.

DEVICE FOR VAPOORIZING AND BURNING LIQUID FUEL.

Application filed July 19, 1924. Serial No. 727,037.

In the practical operation of devices of this nature, where an important part of the service rendered is to be in connection with household needs, with units relatively small and without expert attention, there are several important features to be considered independent of the satisfactory functioning of the apparatus under normal conditions. One of these features has to do with the physical installation of the device; another has to do with automatic and positive control of the liquid fuel supplied to it, so that in case the flame of the burner should be accidentally extinguished the flow of liquid fuel into it will stop by the action of the apparatus itself. Still another of these features has to do with so designing the device that its important parts can easily and quickly be reached for cleaning, for adjustment or for replacement. My invention is particularly adapted to my device for vaporizing and burning liquid fuel, United States Patent 1,397,003, issued November 15, 1921.

As then operated it was necessary to install the entire vaporizing and heat making portion of my device inside of the furnace that was to be heated, for instance. The multiplicity of furnace fire pot and fuel door sizes and shapes made each such installation a problem by itself and put arbitrary and often very narrow limitations on what could be done at all.

Since my device practically consists of two elements, a vapor generator and a main vapor burner to give operative furnace heat, I decided to separate the two to such an extent that the vapor generating part of the apparatus should be installed outside of the furnace that is to be heated and only the main burner be placed inside of it, the pipe, or conduit, which carries vapor to the superimposed main burner in the old form being extended to reach the same main burner in another position.

Exhaustive tests in actual house heating service in from mild to below zero weather, extending over a period of more than two years, have shown not only the practicability of the change and its complete and satisfactory solution of the problem, but have demonstrated very important advantages. I have made no fundamental change in the construction of the device but have added important features made possible by the new

conditions. I have made the casing of vapor generator of fewer parts, more easily assembled and disassembled, and have given that entire portion of the device an independent entity in appearance as well as in fact.

In the form of liquid fuel vaporizer and burner set forth in my United States Patent, Number 1,397,003, the vapor generating part, being enclosed by the walls of the furnace in which it was installed, was left open at two of its opposite sides, or faces. For installation outside of a furnace there must be no open sides, or faces, to the vapor generating part and provision must be made for carrying to the main burner the combustible vapor produced by the vapor generating part and there delivering it to the main burner with little or no loss of heat.

The importance of a supply of heated air as an aid to combustion, while well understood by combustion engineers, is practically disregarded in domestic use. Few furnaces are so devised that any attempt is made in them to benefit by the introduction of heated air into the combustion chamber. Wherever it is done, even by crude methods, the efficiency of the fuel is noticeably increased. The greater the heat of the air supplied the greater is the effectiveness of the fuel consumed. In the form of liquid fuel vaporizer and burner set forth in my United States Patent, Number 1,397,003, heated air is supplied to the main burner with markedly beneficial effect. Air is taken in at the base of the device and carried through hollow sides to be delivered into the main burner case. The conduits for this air passing close to the flame and heat of the auxiliary burner become very hot. In the improved and preferred form of my device air is admitted into a conduit, or duct, opening at the base of one side of the vapor generator and is conducted by that conduit, or duct, up that side of the vapor generator, across its top and down the opposite side, to be delivered into the hollow base of the vapor generator below the auxiliary burner, whence it passes, by openings provided to give of its heated oxygen to the burner there. At the same time I have provided means by which any unchanged portion of this highly heated air that has passed through the vapor generator is conveyed, together with other unburned

gases and the products of combustion, to

be delivered below the main burner, in its furnace location. My preferred way for so conducting this hot air and these gases is by means of a pipe extending from the vapor generator into the furnace and discharging close below the main burner there, said pipe being of considerable size and enclosing the small pipe, or conduit, by which the combustible vapor is carried from the vapor generator to the main burner. By this means the combustible vapor may be carried to a considerable distance, if necessary, without loss of efficiency, thereby giving welcome elasticity to the problem of installation.

15 In the operation of such a device it is necessary that the flow of any required liquid into it shall be under automatic control. Float valves of various kinds have been used for stationary service, some of them with a good measure of success, particularly in units of considerable size. After much experimenting and many practical and extended tests under service conditions, I have developed a form of float 20 valve that has proved to be eminently satisfactory for use where there is no vibration nor jar to assist in keeping the moving parts free to act instantaneously and smoothly, and where the unit to be affected is moderate 25 in size. In my preferred form the valve has but one pin bearing and that large enough to insure sufficiently accurate work by a mechanic of ordinary skill. The thrust of the valve needle is directly downward, the 30 weight of that needle being partly counterbalanced by the weight of the float. This helps to make the valve instantly and effectively responsive to the movement of any liquid and permits the entire valve structure 35 to be relatively small in size. This valve is set so that the water level in the boiler of the device shall be held at a predetermined height, the float valve rising and reducing, or closing, its water intake orifice in exact 40 proportion to the required water level in the boiler; with any reduction below normal of the volume of the boiler water the valve at the intake will automatically open accordingly. A pipe connecting the upper part of 45 the boiler with this valve insures a steam pressure in the valve that helps to maintain the proper balance between the liquid in the boiler and in the valve. By providing that the taper point of the valve needle shall engage only the sharp edge of the orifice for 50 the intake of liquid I make certain that no speck of dirt or any bit of foreign substance shall interfere with the instant and complete closing of this orifice, as might easily happen 55 if the tapered needle were seated at its point of closing in an aperture of similar taper.

60 The float valve as thus described I use preferably for controlling the water flow into the boiler of my device. The flow of liquid fuel into the device I usually prefer

to arbitrarily regulate by means of a needle valve actuated by hand by which it may be graduated to yield a predetermined and constant amount at the will of the user, or may be instantly changed to supply a greater 70 or smaller volume of liquid fuel. A thermostatic attachment may easily be arranged to provide the necessary control. When my device is in operation the water supply automatically adjusts itself to the requirements 75 of the moment; it is by variation in the liquid fuel supply that the amount of heat generated is controlled.

In practice I have found it advantageous to combine both the water control and the 80 liquid fuel control valve in such a manner as to cause them to synchronize and under conditions that automatically stop the flow of liquid fuel if for any cause the fire in the device should intentionally or unintentionally be put out. To accomplish this result I superimpose the liquid fuel control valve on the water control valve and bring the steam connection from the boiler to a point between the two valves. This steam 90 operates in the water control valve precisely as if that valve were acting alone, but by means of the steam pressure on a rubber, or other yielding diaphragm, the pin of a spring push valve is so controlled as to hold 95 the liquid fuel flow at a predetermined volume, to modify it should the steam pressure fall and to stop it completely should the steam pressure disappear. I have found this a never failing safety device under 100 severe tests.

I prefer to close the sides of the vapor generator not covered by the conduit, or duct, by a removable plate on one side and by a door on the other side. For ease of 105 access to the indicated elements of the vapor generator I preferably make that part of its metal casing, which includes the door, and the conduit, or duct, from its air intake opening to its point of discharge into the 110 hollow base, so that it can be lifted bodily from its place, or, by means of hinges basically and anteriorly disposed, be opened downwardly and outwardly.

In the form of my device described in 115 United States Patent, Number 1,397,003 I provided foraminous openings, or holes, in the walls adjacent to the burners for the admission of air to the auxiliary burner and to the main burner. The work of drilling 120 these holes was slow and costly. I now prefer to cast slots in all such parts of the device as being equally effective and much less expensive to make while permitting, with practically no additional cost (any desirable 125 thickness of metal at point of exposure to great heat. These slots are open at their lower end and, in effect, produce in each instance a circle of taper fingers surrounding externally and internally the vapor burner 130

ring I, of the auxiliary burner and the precisely similar ring in the main burner K.

I have found that in furnace installations where the desire is to concentrate the heat rather than to cause any considerable portion of it to spread radially it is better to do away with the spreader plate 1', and the precisely similar one in the main burner K, permitting the combustible vapor in each instance to be discharged upwardly, untrammelled, from the burner ring. A metal collar fitted to their outside circumference directs the oxygen-yielding air flow centrally upward through the burner rings and delivers the volume of flame and heat in a very effectively concentrated form.

I have made various other improvements over the design described in United States Patent, Number 1,397,003, for instance the placing of drain cocks at low points below the main burner and below the auxiliary burner, for the easy removal of any excess liquid or condensate; the giving of a slight drainage pitch to the burner ring of both the main and of the auxiliary burner and the placing of leg supports under the boiler in the vapor generator.

The nature and scope of my present invention will be more fully understood from the following description taken in connection with the accompanying drawings, forming a part hereof, in which:—

Figure 1 is a diagrammatic view partly in cross section and partly in perspective of my entire device.

Fig. 2 is a cross sectional view of the water control valve.

Fig. 3 is a cross sectional view of the liquid fuel control valve and of the top of the water control valve showing how steam from the boiler is delivered between the two valves to exert its pressure simultaneously and uniformly on the diaphragm of the liquid fuel control valve and on the constituents of the water control valve.

Fig. 4 is a perspective view of the vapor generator with a portion of the metal casing partially removed.

Referring to the drawings A represents the metal casing of the vapor generator, B represents the conduit or dust for air, C represents the boiler, one of its supporting legs being shown as c', D represents the superheater, E represents the tubular retort, F represents the reservoir, G represents the liquid fuel control valve, H represents the water control valve, I represents one half of the auxiliary burner ring, K represents the main burner, L represents the auxiliary burner with a portion broken away to show the slots and burner ring.

In operating my device water is admitted to the boiler C, by the pipe h'', from the water control valve H, and there vaporized as described in my United States Patent,

Number 1,397,003, the steam passing into the superheater D, at the boiler outlet c'. By the pipe g, from the liquid fuel control valve G, liquid fuel is fed into the superheater, the trap g', which I usually make very much longer than there shown, helping to maintain the desired and regular flow. Vaporization of the liquid fuel instantly begins on contact with the superheated steam and is continued into the retort E, from which its mixture of the two vapors passes by the pipe e', into the reservoir F, whence by the pipe f, it is conducted to the auxiliary burner, where it discharges by the orifices in the burner ring I, to be burned in the auxiliary burner L, and by the pipe f', to the main burner to be there burned as in the auxiliary burner. The baffle plate a, forces unconsumed air and the products of combustion to circulate in the upper part of the vapor generator before passing downwardly to go through the large pipe a', enclosing the vapor pipe f', to be delivered below the main burner K, the valve g', in the liquid fuel line works with a needle above a graduated scale and is set to permit the passage of a predetermined amount of liquid fuel. The pipe c', carries steam from the boiler and discharges it into an opening below the diaphragm X, of the liquid fuel valve and communicating with the float compartment of the water control valve h'. Air is admitted to the conduit, or duct B, in the metal casing of the vapor generator at the base of one side and passing circumferentially around it is discharged into the hollow base b', whence it passes by openings provided to support combustion in the auxiliary burner L. The water control valve H, receives its liquid by the pipe h', which thence passing around the taper point of the needle h', proceeds, mainly by the duct h', but partially through the needle compartment h', for discharge into the float compartment h'; the float h', being rigidly attached to one end of an arm h'', having but one pin bearing h'', and movably engaging the needle h', by insertion in a notch, or recess h'', moves with no possibility of binding and with a minimum of friction, causing the valve to respond positively and instantly to any movement of the float; the discharge pipe h'', carries water directly into the boiler C, the pipe c', connecting the upper part of this valve with the boiler C, providing balancing steam pressure in that valve. In the combined and superimposed form of valves Fig. 4, the steam pressure from the boiler through the pipe c', is exerted uniformly on the underside of the diaphragm X, and on the contents of the water control valve H, the pressure on the diaphragm X, lifting the pin x', and forcing up the end of the lever x'', which by

the relative depression of its opposite arm x',

causes the valve H to open, admitting water to the boiler C, the pipe c', connecting the upper part of this valve with the boiler C, providing balancing steam pressure in that valve. In the combined and superimposed form of valves Fig. 4, the steam pressure from the boiler through the pipe c', is exerted uniformly on the underside of the diaphragm X, and on the contents of the water control valve H, the pressure on the diaphragm X, lifting the pin x', and forcing up the end of the lever x'', which by the relative depression of its opposite arm x',

pushes down the pin x^4 , in the liquid fuel supply line g , against spring resistance x^5 , thus opening a passage in the liquid fuel supply line g , automatically proportioned to 5 the requirements of the moment and shutting off the liquid fuel flow entirely should actuating pressure disappear from the underside of the diaphragm X. In Fig. 5, the part 10 of the metal casing of the vapor generator which includes the conduit, or duct, from its intake opening to the point of discharge into the hollow base b^2 , is shown partially lifted to expose the vapor generating parts, the pipe x^6 , is for supplying illuminating 15 gas, if available, for giving initial heat when the device is started. If illuminating gas is not available I use some other quick burning substance as described in my United States Patent 1,397,003, November 15, 1921.

20 Having thus described the nature and object of my invention, what I claim as new and desire to secure by Letters Patent is:—

25 1. A device for generating and utilizing fuel gas, having main and auxiliary burners, the main burner being located inside of the furnace that is to be heated and the auxiliary burner, with its adjuncts, together constituting the vapor generator, being located outside of the furnace that is to be heated, the 30 vapor generator consisting of a steam boiler and superheater exposed to the flame and heat of the auxiliary burner, a tubular retort connected at its inlet end to the superheater and at its outlet end to a reservoir 35 from which, through piping means, combustible vapor, or fuel gas, is supplied to the main burner and by another pipe to the auxiliary burner, a liquid fuel supply pipe connected with the superheater, a water supply 40 pipe connected with the boiler; the described vapor generator parts being metal encased, as a unit and having in said metal casing a conduit, or duct, passing up one side, across the top down the opposite side and discharging into the hollow base of said metal 45 casing to give of its oxygen, heated by contact with high temperature surfaces, to add to the efficiency of combustion in the auxiliary burner, substantially as and for the 50 purposes described.

55 2. A device for generating and utilizing fuel gas having main and auxiliary burners, the main burner being located inside of the furnace that is to be heated and the auxiliary burner, with its associate parts, together constituting the vapor generator, being located outside of the furnace that is to be heated, the vapor generator consisting of a 60 steam boiler and superheater exposed to the flame and heat of the auxiliary burner, a tubular retort connected at its inlet end to the superheater and at its outlet end to a

reservoir from which, by piping means, combustible vapor, or fuel gas, is supplied to 65 the main burner and, by another pipe, to the auxiliary burner, a liquid fuel supply pipe connected with the superheater, a water supply pipe connected with the boiler, the described vapor generating parts being enclosed in metal and having in said metal casing a conduit or duct, with an opening for the admission of air, said conduit, or duct, being exposed to the flame and heat of the auxiliary burner and discharging the 70 highly heated air that passes through it in a position to give of its oxygen to the auxiliary burner, a baffle plate in the vapor generator to force heated air and the products of combustion to circulate in upper parts of 75 the vapor generator before being carried to the main burner in a pipe, enclosing said vapor supply pipe, the auxiliary and the main burners receiving air through slots, or openings, in the metal internal and external walls between which each burner ring delivers combustible vapor, substantially as 80 and for the purposes described.

85 3. A device for generating and burning fuel gas having main and auxiliary burners, the main burner being located inside of the furnace that is to be heated and the auxiliary burner being located outside of the furnace that is to be heated, the vapor generator consisting of a steam boiler and superheater exposed to the flame and heat of the auxiliary burner, a tubular retort connected at its inlet end to the superheater and at its outlet end to a reservoir from which, by piping means, combustible vapor, or fuel gas, is supplied to the main burner and, by another pipe, to the auxiliary burner, a liquid fuel supply pipe connected with the superheater and a water supply pipe connected 90 with the boiler each of said supply pipes having independent valvular control but both valves being connected by piping means with the boiler of the vapor generator in such manner, that steam from the boiler affects 95 both valves synchronously, the described vapor generator parts being encased in metal and having in said metal casing a conduit, or duct, with an opening at one end for the admission of air, which air after passing 100 circumferentially around the vapor generator, discharges into the hollow base of the said metal casing to give of its oxygen, heated by contact with high temperature surfaces, to add to the efficiency of combustion in the auxiliary burner, substantially as 105 and for the purposes described.

110 In witness whereof, I have hereunto set my signature.

MANLY M. GILLAM.
